UNITED STATES PATENT OFFICE

PAUL ROHRMANN, OF BRESLAU, GERMANY

CHAIR

Application filed October 9, 1928, Serial No. 311,381, and in Germany October 11, 1927.

This invention relates to chairs in which a folded table plate forms the back of the chair. When unfolded, the improved chair serves as table.

5 At the back of the chair two suitably curved longitudinal bars are stationarily fixed to the back legs of the chair, for instance by screws and bolts. Said two back rods must be so curved, to enable the easy reception of the folded table plate when the improved chair has to serve as seat.

10 When unfolded, the table plate is supported at the front of the chair by means of a U-shaped frame; which latter is pivotally fixed to the front part of the chair. The table plate per se is formed of two plates articulated in any suitable and reliable manner at the centre where both plates join. One half of the table plate is rigidly connected to the 15 two free upper ends of the U-shaped frame, whereas the other half of the table plate is laid over said rigidly connected first half of the table plate. In folded position the U-shaped frame forms the flash continuation of 20 the seat and the folded table plate forms the back of the chair.

25 Furthermore a drawer is provided underneath the seat, which drawer is so constructed that it may be drawn out at the right as well as at the left of the chair frame.

30 One form of execution of the present invention is shown, by way of example, in the accompanying drawings, wherein—

35 Fig. 1 is a top view of the improved chair, the table plate being in its folded position, serving as back of the chair.

40 Fig. 2 is a side elevation of the chair, the table plate being in unfolded position, the whole serving as table.

45 Fig. 3 is a front elevation of the chair, according to Fig. 2.

Fig. 4 illustrates the chair seen from behind, the table plate being in its folded position and serving as back of the chair.

50 The frame of the chair is, as usual, made of the seat 1 with two front legs 2 and two rear legs 3. At the back of the two rear legs 3 two suitably curved longitudinal bars 4 and 5 are stationarily fixed, for instance by means of bolts and screws. Said two longitudinal

curved bars 4 and 5 are connected together at the top by means of a small transverse rod 6, the extremities 7 and 8 of which extend transversely out of the curved bars. At the middle of said transverse rod 6 a portion 9 is cut out to receive a knob of the table plate, when folded together, and further in order to avoid any injuring of the finger during manipulation.

55 The pivotable U-shaped frame 10 must be so constructed that it fits the seat 1 of the chair and, when laid down onto the seat, forms the continuation thereof. Said frame 10 is pivotally mounted on the front part of the chair in such a manner that it may easily 60 be raised and lowered. When raised, said frame butts with its front transverse part against the front legs of the chair, thus giving the table plate, when unfolded, a firm support. The table plate per se consists of two 65 plates 11 and 12 suitably articulated so as to give a reliable hold to the entire table plate. The plate 11 is rigidly connected in any suitable manner, to the two upper free extremities of the U-shaped frame 10. The second 70 plate 12, articulatively connected to the first plate 11, is provided, at its bottom surface with two rods 13, 14, each of which is provided with one dove-tailed incision 15, 16 so formed and situated, that the extensions 7 and 75 8 of the transverse rod 6 fit into said incisions of the table-plate-rods 13, 14 when the table plate is unfolded and put in position (Fig. 2).

80 A knob 17 is so situated at the top edge of the bottom surface of the plate 12 that it fits into the cut-out portion of the transverse rod 6 when the table plate is in its position serving as back of the chair, the cut-out portion being so curved, that still sufficient room is left to enable the gripping of the knob with 85 the finger for manipulation.

89 Between the legs of the chair a drawer 18 is provided and so constructed that it may be pulled out, by means of its knobs 19, 20 either from the right- or left hand side of the chair.

95 The operation is as follows—

99 Suppose the table plate is folded together and serves as back of the chair. One grips the knob 17 with one finger of the right hand and lifts the folded table plate 11, 12, which 100

thus automatically raises the U-shaped pivotable frame 10. The back of the chair, e. g. the folded table plate, is raised until the front transverse part of the U-shaped frame 10 butts against the front part of the chair, that is to say until the frame stands vertical. The plate 12 of the table plate is then unfolded, e. g. brought into the stretched position (Figs. 2 and 3), until the dove-tailed incisions 15, 16 underneath the plate 12 of the table plate engage the extensions 7 and 8 of the transverse rod 6. The table plate is thus securely fixed in its position.

To bring the table plate into its original position, e. g. as back of the chair, it is merely necessary to grip the knob 17 with one finger, to fold the plate 12 over the plate 11 and to push the thus folded table plate into the curved portion of the longitudinal bars 4 and 5 until the lower edge of the folded table plate rests on the lowest curved portion of the longitudinal bars 4 and 5. Once the folded table plate in its position of rest, the U-shaped frame 10 will form the flush continuation of the seat 1 and the chair can serve as seat.

Evidently the several parts of the improved chair may be otherwise disposed to realize the object of the present invention without departing from the scope of this invention as the form of execution shown in the drawings is merely by way of example.

I claim:—

An improved chair comprising a seat, two front legs, two rear legs in combination with two suitably curved bars fixed to the two hind legs, a small transverse rod the extremities of which extend sideways out of the two curved bars, a frame pivotally mounted on the front part of the chair, a table plate consisting of two plates of which the one plate is rigidly connected to the upper free ends of the pivotable frame, and the second plate hingedly connected to the first mentioned plate so as to enable the folding over of said plate onto the first plate, two rods on the bottom surface of the second plate, one dove-tailed incision in each of said two rods to engage the extensions of the transverse rod when the table plate is in stretched position.

In testimony whereof I affix my signature.

PAUL ROHRMANN.
